UNITED STATES PATENT OFFICE.

FREDERICK I. JOHNSON, OF FITCHBURG, MASSACHUSETTS, ASSIGNOR TO
MARY ELIZABETH JOHNSON, OF FITCHBURG, MASSACHUSETTS.

DESIGN FOR A CYLINDER-COVER FOR FIREARMS.

SPECIFICATION forming part of Design No. 35,646, dated January 28, 1902.

Application filed September 20, 1900. Serial No. 30,632. Term of patent 14 years.

To all whom it may concern:

Be it known that I, FREDERICK I. JOHNSON, a citizen of the United States, and a resident of Fitchburg, in the county of Worcester and Commonwealth of Massachusetts, have invented a new and useful Design for Cylinder-Covers for Firearms, of which the following is a specification, reference being had to the accompanying drawings, forming part thereof.

10 Figure 1 is a perspective view of a cylinder-cover for firearms embodying my new design. Fig. 2 represents a front view showing the outer side of the cover, and Fig. 3 is a rear view showing the inner side of the cover.

15 Similar reference-letters refer to similar parts in the different views.

20 My new design relates to a perforated cover for inclosing one side of the revolving cylinder of a firearm, and the principal feature of my design consists of a series of circular holes or perforations A through the body of the cover and also a series of holes or perforations B in one end of the cover. The cover

itself consists of a body portion C, curved in the arc of a circle and provided with heads 25 D and E. The holes A pass through the body portion C and are disposed in straight diagonal lines across the body of the cover. The heads D and E have their outer surfaces slightly curved, and the head E is provided 30 with a series of holes B, which extend through the head, as shown.

Having described my invention, what I claim as new, and desire to secure by Letters Patent, is—

35 The design for a cylinder-cover for revolving firearms, as herein shown and described.

In testimony whereof I have signed my name to this specification, in the presence of two subscribing witnesses, this 17th day of 40 September, A. D. 1900.

FREDERICK I. JOHNSON.
